Inventor

Egbert A. Clark,
A. L. Strong.

Attorney

UNITED STATES PATENT OFFICE.

EGBERT A. CLARK, OF WASHINGTON, DISTRICT OF COLUMBIA.

CUFF-HOLDER.

SPECIFICATION forming part of Letters Patent No. 743,617, dated November 10, 1903.

Application filed May 9, 1903. Serial No. 156,334. (No model.)

To all whom it may concern:

Be it known that I, EGBERT A. CLARK, a subject of the King of England, residing at Washington, in the District of Columbia, have invented certain new and useful Improvements in Cuff-Holders; and I do hereby declare the following to be a full, clear, and exact description of the invention, such as will enable others skilled in the art to which it appertains to make and use the same.

This invention relates to new and useful improvements in cuff-holders, garment-supporting devices, &c.; and it consists in the provision of a clasp comprising two spring-actuated jaws adapted to engage the lining of a coat-sleeve and provided with a flexible spring-arm designed to frictionally engage the edge of a cuff and hold the same in any suitable position with relation to the end of the sleeve, whereby the cuff may be easily adjusted to project beyond the end of the sleeve or be held within the sleeve.

The invention consists, further, in various details of construction and arrangements of parts, which will be hereinafter fully described, and then specifically defined in the appended claims.

I have illustrated my invention in the accompanying drawings, which, with the letters of reference marked thereon, form a part of this application, and in which drawings similar letters of reference indicate like parts in the views, in which—

Figure 1 is a perspective view showing the application of my cuff-holding device. Fig. 2 is an enlarged view of the device in side elevation. Fig. 3 is a central longitudinal section through the same. Fig. 4 is a perspective view of the cuff-holding device. Fig. 5 is a perspective view showing a slight modification in details of construction of the cuff-holder, and Fig. 6 is a detail sectional view showing the manner in which the friction-plate in Fig. 5 is held to one of the jaws of the clasp.

Reference now being had to the details of the drawings by letter, A and A' designate the two jaws of the clasp, each of which is provided with integral ears a, which are apertured to receive the pin B, on which the two jaws are pivotally mounted. Said jaw

A has a series of serrations C along one end thereof, and the jaw A', which is made, preferably, of a single piece of metal bent upon itself at D and has formed in the edge of the metal which is thus bent a series of serrations D', designed to intermesh with the serrations C, formed in the end of the jaw A. The portion of the jaw A' which is bent back upon the latter and designated in the drawings by letter E in Figs. 1 to 4, inclusive, is flexible and is bent at an angle at E', with substantially one-half its length bearing flat against the outer face of the jaw A', thus providing a considerable area of contact-surface 65 for engagement with the inner face of a cuff, which is to be clamped by said flexible arm to the jaw A'. The free end of the flexible arm E is outwardly bent, as at H, while the adjacent end of the jaw A' is extended beyond the curved end H, affording a slight space serving to guide the edge of the cuff between the flexible arm and the jaw A' when the device is applied to the cuff. In order to obviate any interference of the rear end 70 of the jaw A with the lining of the coat, the end of said jaw is preferably inwardly curved, as shown.

In Figs. 5 and 6 I have shown a slight modification of my device, in which instead of making the flexible arm A' of one piece I make the plate E' similar in construction in all essential features to the arm E, excepting that it is a separate piece and provided with integral lugs K', one on either side thereof, 80 which are adapted to be bent over the edge of the jaw A' and engage notches N, formed in the opposite edges of the jaw A', as shown clearly in the detail view Fig. 6. In the modification illustrated in Fig. 5 the serrations 85 would be formed in the end of the jaw A' instead of in the portion which is bent upon itself, as disclosed by Figs. 1 to 4, inclusive.

In applying my device to the sleeve of a coat one of the meeting edges of the cuff is slipped between the flexible bar E and the adjacent jaw A', said bar yielding to allow the edge of the cuff to enter, and the cuff will be securely held by frictional contact between the members. After the device has 95 been applied to the cuff the latter is inserted in the end of the sleeve of a coat, and the

jaws of the clasp may be easily opened by the operator depressing the outer ends thereof and pushing the teeth of the jaws against the lining in order to grasp a fold of the lining 5 between the jaws, and after pressure is relieved from the latter the clasp will be held in a fixed position to the portion of the lining engaged by the clasp. The opening and closing of the jaws of the device may be easily 10 accomplished by the operator inserting one finger or thumb inside a cuff, while a second finger or thumb may be applied to the outside of the sleeve directly adjacent to the clasp, and by depressing the ends and pushing 15 the clasp toward the lining the clasp may be adjusted at any desirable location with reference to the end of the sleeve. When the clasp is thus attached to the lining, it will be evident that the distance at which it is desired 20 to have the cuff extend beyond the end of the sleeve may be regulated by pulling or pushing upon the cuff, the latter sliding between the flexible bar and the adjacent jaw, but at all times being held with sufficient frictional force to retain the cuff in its adjusted 25 position.

By the provision of my improved cuff-holding device it will be observed that the fastening of the cuff to the shirt-sleeve is entirely 30 dispensed with, and the cuff may be held attached to the sleeve after the wearer removes his coat.

While I have shown the invention as adapted for use particularly as a cuff-holder, it will 35 be understood that the same may be utilized for various purposes in supporting garments—as, for instance, in connection with trousers, skirts, &c.—and in which application of its use the jaws could be clamped to 40 any suitable portion of a garment with the flexible arm or bar disposed in a vertical po-

sition to utilize a hook over which a loop could be caught for supporting any garment.

It will also be understood that while I have shown a particular construction of garment-supporting device embodying the principle of my invention I may alter the construction of the device in various details, if desired, without departing from the spirit of the invention. 45 50

Having thus fully described my invention, what I claim as new, and desire to secure by Letters Patent, is—

1. A cuff-supporting device comprising a pair of spring-actuated pivotal jaws one of 55 which is serrated, a flexible clamping-plate fixed at one end to one of said jaws adjacent to its serrated portion, a portion of said clamping-plate held yieldingly against the adjacent jaw to which it is fixed and opposite the pivotal points of the jaw, as set forth. 60

2. A cuff-holding device comprising two spring-actuated pivotal jaws, one of said jaws being bent upon itself along its clamping edge, and forming a flexible plate yieldingly 65 held against the adjacent face of the jaw of which it is an integral part, and adapted to frictionally engage and hold a cuff against the last-named jaw. 70

3. A cuff-holder comprising two spring-actuated pivotal jaws, one of which is bent upon itself and forms a flexible plate held yieldingly against the adjacent face of the jaw of which it is an integral part, a series of teeth 75 in the edge, which is formed by bending the jaw upon itself, as shown and described.

In testimony whereof I affix my signature in presence of two witnesses.

EGBERT A. CLARK.
